CHARLES B. GILMORE.
By Atty. N. Dubois.

UNITED STATES PATENT OFFICE.

CHARLES B. GILMORE, OF BLOOMINGTON, ILLINOIS.

BALLOT-BOX.

SPECIFICATION forming part of Letters Patent No. 795,114, dated July 18, 1905.

Application filed October 4, 1904. Serial No. 227,144.

To all whom it may concern:

Be it known that I, CHARLES B. GILMORE, a citizen of the United States, residing at Bloomington, in the county of McLean and State of Illinois, have invented certain new and useful Improvements in Ballot-Boxes, of which the following is such a full, clear, and exact description as will enable others skilled in the art to which it appertains to make and use my said invention.

My invention relates to ballot-boxes which are usable with voting-machines or the like.

The purposes of my invention are to provide novel and improved means for connecting the ballot-box with the compartment of the voting-machine in which it is contained in such manner that any attempt to remove the ballot-box from the compartment will cause immediate closing and locking of the closure of the ballot-box, to provide improved means for sealing the ballot-box, to provide improved means to facilitate the removal of balls deposited in the ballot-box, and to provide other novel and useful devices.

With these ends in view my invention consists of the novel features of construction and combinations of parts shown in the annexed drawings, to which reference is hereby made, and hereinafter particularly described, and finally recited in the claims.

Referring to the drawings, Figure 1 is an end elevation of a series of ballot-boxes in position in the compartments of a voting-machine. Fig. 2 is a horizontal section on the line 2 2 of Fig. 3. Fig. 3 is a side elevation of a single ballot-box. Fig. 4 is a vertical section on the line 4 4 of Fig. 3; and Fig. 5 is an enlarged partial vertical section on the line 5 5 of Fig. 1, the handle and the locking-bolt being shown in elevation.

Similar reference-letters designate like parts in all of the views.

In the drawings I have shown only so much of the voting-machine as is necessary to illustrate the connection of the ballot-box therewith.

The cabinet A of the voting-machine is a rectangular box having vertical partitions a, which divide the box into compartments each adapted to accommodate a ballot-box. The

ballot-box B is preferably of metal and has vertical partitions b, dividing the box into a series of ball-receptacles each adapted to contain a series of rows of balls arranged one above the other, each row containing a predetermined number of balls, preferably ten. The sides b' of the ballot-box are of glass or other transparent material, through which the balls are visible. A cap B', secured on the box B by a screw-bolt b² or other suitable securing device, has in its under side a longitudinal channel b³, in which the closure B² slides. The cap B' is pierced by a series of holes b⁴, which respectively communicate with the compartments of the ballot-box. The closure B² has a series of perforations b⁵, which respectively register with the perforations b⁴ through the cap when the closure is pushed inward and occupies the position shown in Fig. 3. The closure B² is also pierced by holes b⁶ and b⁷, which respectively receive a pin e at the upper end of the locking-bolt E and the pin d at the upper end of the handle D.

The handle D is connected with the front of the box B by a hinge d' and has a pin d, which extends upward through the hole b' in the closure B². Pulling on the handle D causes the closure to slide outward and bring the hole b⁶ into such position that the pin e of the bolt E will enter the hole and lock the closure against inward movement.

In the end of the box B is a vertical channel b⁸, in which vertical locking-bolts E and E' slide freely. A stationary lug b⁹ in the channel b⁸ projects through a slot e' in the bolt E and supports a spring E', which is compressed when the upper end of the pin e lies under the closure B² and reacts to raise the bolt E when the closure is pulled outward and causes the pin e to enter the hole b⁶. The lower bolt E' has a chisel-shaped extension e'', which fits in a hole a' in the base of the cabinet and locks the ballot-box in the compartment when the bolt E' is depressed. Near the lower end of the bolt E is a rectangular slot e³, in which a T-shaped extension e⁴ of the bolt E' slides freely.

When the closure B² is pulled outward by pulling on the handle D, the spring E' acts to raise the bolt E and cause the pin e to enter

the hole b^6 and also to raise bolt E' , so as to withdraw the extension e^2 from the hole a' . When the parts are in this position, the ballot-box may be removed from the cabinet. When 5 it is desired to replace the box in its compartment in the voting-machine, the closure is first restored to its first position, as hereinafter explained. The ballot-box may then be placed in its compartment and pushed inward, when 10 the chisel-shaped part e^2 , riding on the base of the cabinet, will raise the bolt E' until the extension e^2 of the bolt comes into registry with the hole a' , when the bolt will gravitate and cause the extension e^2 to enter the hole a' 15 and lock the ballot-box in the compartment of the voting-machine until the bolt E' is again lifted by the bolt E , as already described. The bolt E slides upward to lock the closure and in doing so pulls the bolt E' upward so 20 as to withdraw the extension e^2 from the hole a' . When the bolt E' is pulled downward by an instrument inserted in the hole e^5 , it pulls the bolt E downward, so that the upper end of the pin e is below the closure B^2 and 25 presses the spring E^2 , so that the spring will act to raise the bolt E when the closure B is moved outward.

At the lower end of the ballot-box is a door B^3 , connected with the box by a hinge b^{10} . A 30 hasp and shield B^4 , suitably connected with the door B^3 , has a slot b^{11} . A stationary stud B^5 on the box B fits in the slot b^{11} of the hasp B^4 and has an eye b^{12} , through which the wire of an ordinary seal B^6 may be passed and sealed 35 to secure the hasp against unauthorized opening of the door. The part B^4 serves as a hasp to secure the door B^3 and also serves as a shield to cover and protect the lower part of the slide E' , so that the slide cannot be moved 40 downward from the outside without breaking the seal and removing the hasp and shield.

After the closure B^2 has been moved outward it is necessary to withdraw the pin e before the closure can again be pushed inward. 45 To accomplish this result, I provide near the lower part of the bolt E' a hole e^5 , which is covered and protected by the hasp B^4 , so that the hole is accessible only when the hasp is removed. The hasp being removed, a pin or 50 other suitable instrument inserted in the hole e^5 will serve to pull down the bolt E' and cause it in turn to pull down the bolt E , so as to withdraw the pin e from the hole b^6 . The closure may then be pushed inward to its initial 55 position.

When it is desired to remove the balls from the ballot-box, the seal is broken, the hasp is removed, and the door B^3 is opened, so that the balls may be removed from the lower end 60 of the ballot-box.

The operation of the device is as follows: The ballot-box being empty and the door open, a pin or other suitable instrument is inserted in the hole e^5 and pushed downward, so as to 65 cause the withdrawal of the pin e from the

hole b^6 in the closure. The closure is then pushed inward to its limit, thereby bringing the holes b^5 through the closure into registry with the perforations b^4 in the cap. The door B^3 is then closed, the hasp B^4 is placed on the 70 stud B^5 , and the wire of the seal B^6 is passed through the eye b^{12} and sealed. The ballot-box is then inserted in its compartment of the voting-machine. Balls may then be deposited through the perforations b^4 and b^5 into the several compartments of the ballot-box. When 75 the operation of voting is completed, the proper official pulls on the handle D and withdraws the ballot-box from its compartment in the voting-machine, and the act of withdrawing the box closes the openings communicating with the compartments of the ballot-box and locks the closure against further use until the seal has been broken, the door opened, the balls removed, and the door again closed, as 80 already explained.

Having fully described my invention, what I claim as new, and desire to secure by Letters Patent, is—

1. In a ballot-box, the combination of a partitioned box, a perforated cap secured on said box, a slidable closure having holes registrable with the perforations in said cap, a handle mounted on said box and connected with said closure and a slidable bolt engaging with said closure to lock same against inward movement, as set forth. 90

2. In a ballot-box, the combination of a box having compartments, a perforated cap secured on said box, a correspondingly-perforated closure slidable in said cap, a handle mounted on said box and connected with said closure, a slidable bolt locking said closure against inward movement, a door closing the compartments of said box, a shield connected 100 with said door and covering said slide, and means for securing said shield, as set forth. 105

3. The combination of a box having a channeled wall, coacting bolts slidable in the channel of the wall of said box, means for moving 110 said bolts simultaneously upward, a cabinet having a compartment containing said box, a perforated cap on said box, and a perforated closure slidable in said cap; one of said bolts acting to lock said closure and the other acting 115 to lock the box in its compartment in the cabinet, as set forth.

4. A ballot-box comprising a box having a channel and compartments, a closure having holes registrable with the compartments of 120 said box, a handle mounted on said box and connected to operate said closure, interacting bolts slidable in the channel of said box and adapted to lock said closure, also adapted to secure the ballot-box in a compartment in 125 which said box is contained, a door controlling access to the compartments of said box, a shield connected with said door and controlling access to said bolts and means for sealing said shield in connection with said box, as set forth. 130

5. A box having a channel and a lug in said channel, a slideable upper bolt, a spring supported on said lug and acting to raise said upper bolt, and a lower bolt slideable in said channel and interlocking with and movable relative to said upper bolt; in combination with a movable closure adapted to be locked by said upper bolt and a stationary securing device adapted to receive the end of said lower bolt, as set forth.

6. A slideable upper bolt having a slot, a slideable lower bolt having a T-shaped extension sliding in the slot of said upper bolt, and a spring compressible by downward movement of the lower bolt and acting to raise both bolts; in combination with a box having a channel in which said bolts slide, a member slideable on said box and adapted to be locked

by said upper bolt, and a stationary securing device coacting with said lower bolt, as set forth.

7. A ballot-box comprising a box having compartments, a channeled cap secured on said box, a closure slideable in the channel of said cap, a door hinged on said box, a hasp connected with said door, a sealing device securing said hasp on said box, and a handle pivotally connected with said box and connected with said closure, as set forth.

In witness whereof I have hereunto subscribed my name, at Bloomington, Illinois, this 27th day of September, 1904.

CHARLES B. GILMORE.
